W. C. WACHTER.

STRAW DECK FOR SEPARATORS.

APPLICATION FILED FEB. 8, 1913. RENEWED MAR. 28, 1914.

1,114,073.

Patented Oct. 20, 1914.

UNITED STATES PATENT OFFICE.

WILLIAM C. WACHTER, OF MEDICINE LAKE, MONTANA.

STRAW-DECK FOR SEPARATORS.

1,114,073.

Specification of Letters Patent.

Patented Oct. 20, 1914.

Application filed February 8, 1913, Serial No. 747,127. Renewed March 28, 1914. Serial No. 828,099.

To all whom it may concern:

Be it known that I, WILLIAM C. WACHTER, a citizen of the United States, residing at Medicine Lake, in the county of Valley 5 and State of Montana, have invented certain new and useful Improvements in Straw-Decks for Separators, of which the following is a specification, reference being had to the accompanying drawings.

10 This invention relates to improvements in straw decks for grain separators and has for its primary object to provide an improved deck or rack construction whereby the grain will be quickly and effectually 15 separated from the straw.

Another object of the invention resides in the provision of a simple and durable straw deck construction which may be applied to the ordinary grain threshing machines now 20 in common use without necessitating any material alterations in their construction.

With the above and other objects in view as will become apparent as the description proceeds, the invention consists in certain 25 constructions, combinations and arrangements of the parts that I shall hereinafter fully describe and claim.

For a full understanding of the invention, reference is to be had to the following 30 description and accompanying drawing, in which—

Figure 1 is a top plan view of a straw deck or rack embodying the present invention; Fig. 2 is a bottom plan view thereof. 35 Fig. 3 is a longitudinal section of one of the rack sections, and Fig. 4 is a transverse section thereof taken on the line 4—4 of Fig. 3.

Referring in detail to the drawing, 5 designates a series of deck or rack sections. 40 I have illustrated in the drawings, six of these separating sections, though it will be understood that a greater or less number of the same may be employed if desired. As these deck sections are all of the same construction, the detail description of one of them will suffice for all.

In constructing the deck or rack section, I employ the two side walls indicated at 6 which are arranged in parallel relation. 50 These side walls may be of any desired length in accordance with the size and capacity of the thresher and are provided upon their upper edges with coarse teeth 7. The lower edges of these side walls have 55 relatively fine teeth 8 provided thereon and to the inclined edges of these teeth, the

transverse plates 9 are fixed at their ends. It will thus be seen that these plates are spaced from each other and constitute a riddle through which the grain which has 60 been separated from the straw falls upon a lower oscillating screen, (not shown) where the chaff is separated from the grain, as is common in machines of this character.

The upper edges of the side walls 6 are 65 downwardly inclined or curved at their forward ends as indicated at 10 and at their rear ends, these walls are upwardly curved as shown at 11 to elevate the straw at its discharge point.

The deck or rack sections 5 are oscillated 70 through the medium of the crank shafts 12 which extend transversely beneath the deck sections. The cranks of these shafts alternately extend in opposite directions and 75 are mounted in suitable journal boxes 13 secured to the under side of each of the straw decks. Two of these crank shafts are employed, the same being located adjacent the opposite ends of the rack. To the end 80 of one of said shafts, a belt wheel or pulley 14 is secured for engagement by a suitable driving belt 15 extending from a suitable source of power. The opposite ends of the 85 crank shafts are each provided with the wheels or disks 16 to which the opposite ends of the pitmen 17 are eccentrically connected. It will thus be apparent, that when the crank shafts are rotated, the alternate 90 rack or deck sections are moved in relatively 95 opposite directions vertically and longitudinally. Thus the straw is moved longitudinally upon the toothed upper edges of the side walls of the deck sections and thoroughly agitated and broken to dislodge the grain therefrom. This grain falls downwardly upon the obliquely inclined spaced plates 9 constituting the bottom of each deck section and through the spaces between 100 said plates.

From the foregoing, it is believed that the construction and manner of operation of my improved straw rack or deck will be fully understood.

The device is comparatively simple in its 105 construction, and by providing the comparatively high side walls, the straw is carried longitudinally over the rack in spaced relation to the riddle plates, so that a more effectual separation of the grain 110 from the straw will be obtained.

The device as a whole is simple and du-

able in its construction and may be produced at small manufacturing cost.

While I have shown and described the preferred form and construction of the several elements employed, it will be obvious that the invention is susceptible of considerable modification without departing from the essential features or sacrificing any of the advantages thereof.

10 Having thus described the invention, what is claimed is:

A straw deck for grain separators comprising a plurality of curved sections, each of said sections consisting of a pair of spaced side walls provided upon their upper edges with teeth and upon their lower edges with relatively fine teeth, the teeth on the

lower edges of said walls having inclined edges facing forwardly, said side walls having the upper edges curved downwardly at 20 their forward ends and the lower edges curved upwardly at the rearward ends thereof, ridge plates secured at their ends to the inclined edges of the teeth on the lower edges of the side walls for arrangement in spaced 25 relation to one another, and means in connection with said sections to alternately reciprocate the same in opposite directions.

In testimony whereof I hereunto affix my signature in the presence of two witnesses. 30

WILLIAM C. WACHTER.

Witnesses:

JOSEPH PUMALO,
M. K. POWERS.
